DESIGN FOR A COMBINED CLOCK AND ADVEETISING SIGN

Ralph Landau, New York, N. Y.

Application October 25, 1939, Serial No. 87,846

Term of patent 3½ years

To all whom it may concern:

Be it known that I, Ralph Landau, a citizen of the United States and a resident of the Borough of Manhattan, city, county, and State of New York, have invented a new, original, and ornamental Design for a Combined Clock and Advertising Sign, of which the following is a specification, reference being had to the accompanying drawing forming a part thereof.

Figure 1 is a front elevational view of the combined clock and advertising sign showing my new design;

Fig. 2 is an end elevational view thereof.

I claim:

The ornamental design for a combined clock and advertising sign, substantially as shown.

RALPH LANDAU.
